UNITED STATES PATENT OFFICE.

PASQUALE J. SASSANO, OF EAST ORANGE, NEW JERSEY.

CARBURETER.

1,086,226.

Specification of Letters Patent. Patented Feb. 3, 1914.

Application filed August 23, 1912. Serial No. 716,788.

To all whom it may concern:

Be it known that I, PASQUALE J. SASSANO, a citizen of the United States, residing at East Orange, in the county of Essex and State of New Jersey, have invented new and useful Improvements in Carbureters, of which the following is a specification.

The present invention has relation to carbureters for internal combustion engines, the principal object in view being to avoid the use of the auxiliary air intake generally provided in the construction of the ordinary carbureter.

A further purpose of the invention is to simplify the construction and minimize the number of parts and to provide an arrangement whereby the carbureter is automatic in adapting itself to the speed of the engine, whether the same is running slow or fast.

The invention consists of the novel features, details of construction and combination of parts, which hereinafter will be more particularly set forth, illustrated in the accompanying drawing, and pointed out in the appended claims.

Referring to the drawing, forming a part of the specification, Figure 1 is a vertical central longitudinal section of a carbureter embodying the invention. Fig. 2 is a top plan view. Fig. 3 is a detail view of the piston control. Fig. 4 is a plan view of the piston.

Corresponding and like parts are referred to in the following description, and indicated in all the views of the drawing, by the same reference characters.

The carbureter comprises separate and distinct parts such as a fuel mixer, a float control and a fuel regulator. The fuel mixer embodies a Venturi tube 2 which is surrounded by means of a jacket C through which a heating medium is caused to circulate to facilitate the commingling of the fuel and air and to insure the thorough vaporization of the fuel. The Venturi tube is provided at its upper end with an attaching flange 3 and within the upper portion of such tube is arranged the throttle 1 and an annular stop h, the latter consisting of a split ring sprung into a groove formed in the inner wall of the tube, said ring forming

a stop to limit the upward movement of the piston B. A bar 4 extends across the lower end of the Venturi tube and has an opening 5 through which the fuel passes into the spray nozzle F, which is located centrally within the lower portion of the Venturi tube and is connected at its lower end with the bar 4. The spray nozzle terminates about in the plane of the contracted portion of the Venturi tube. A priming cup j is connected with the bar 4 by means of a stem 6 in which is mounted a needle valve H by means of which the flow of the fuel through the opening or passage 5 is regulated. A space i is formed between the lower end of the Venturi tube 2 and the priming cup j. The piston B is arranged to move freely within the Venturi tube above the flared portion and is provided near its outer edge with a plurality of openings G which incline to the vertical in such a manner as to impart to the jets of air escaping therefrom a spiral or gyrating motion to insure a thorough commingling of the air and fuel. The piston B has a central opening in which is fitted a hollow stem A which telescopes with the spray nozzle F. A damper K co-operates with the piston B to vary the effective size of the openings G to meet varying conditions, such as speed of the engine and the character of the fuel and nature of the air to be mixed therewith. Openings K are formed in the sides of the hollow stem A at a point intermediate above the spray nozzle F when the parts are in normal position and the engine is running at slow speed. A deflector t is mounted upon the hollow stem A immediately above the openings K in the sides thereof, said deflector being of inverted cup shape and of a diameter to close the openings through the contracted portion of the Venturi tube, thereby causing the air to pass through the openings K and upward through the hollow stem A.

The float control consists of a chamber E which has its lower portion connected with one end of the bar 4. A cover a closes the upper end of the chamber E. A guide pin m is pendent from the cover a and directs the float D in its vertical movement. The

upper portion of the guide pin is reduced and threaded and receives a nut *n* by means of which the guide pin is secured to the cover. The float *D* may be of any variety so long as it moves by the change of level of the liquid fuel contained in the chamber *E* and serves to regulate the supply of fuel.

A chambered extension *7* is provided at one side of the chamber *E* and has a fuel inlet in its bottom which is closed by means of a valve *8*. The float lever *g* pivoted at *9* has one end connected with the valve *8* and its opposite end arranged to engage the float *D*. A plunger *b* is arranged to operate within the chambered extension *7* and is normally pressed downward by means of an expansible helical spring *10* so as to hold the valve *8* closed. The plunger *b* has a stem *b'* which passes through the helical spring *10* and a plug *c* threaded into the upper portion of the chambered extension *7* and engaging the upper end of the spring *10*. The plug *c* is adjustable to admit of varying the tension of the spring *10* and is secured in the adjusted position by means of a jam nut *d*. A chamber *P* is formed below the valved bottom of the chambered extension *7* and has a coupling *f* and a drain cock *11* fitted thereto. The feed pipe from the fuel tank is adapted to be coupled to the inlet *f* in the usual way.

The operation of the carbureter is as follows: The parts when assembled appear substantially as shown in the accompanying drawing. When the fuel in the chamber *E* is at the predetermined level the float *D* is lifted, thereby permitting the spring *10* through the plunger *b* to hold the valve *8* seated. At the same time the fuel within the spray nozzle *F* extends to within a short distance approximating one-eighth of an inch of the upper or delivery end. When the engine is running at slow speed air is drawn upward into the space *u* of the Venturi tube 45 surrounding the spray nozzle *F* and passes through the openings *K* of the hollow stem *A*, thence to the engine. The suction created by the air causes a small portion of the fuel to be drawn from the spray nozzle *F* and such fuel mixing with the air produces the combustible mixture for use in the engine. As the speed of the engine increases the piston *B* is caused to move upward, thereby increasing the passage through the Venturi tube by moving the deflector *t* away from the contracted portion of said tube. This also increases the suction through the tube with the result that a greater amount of fuel is caused to discharge from the spray nozzle *F*. The air passing through the openings *G* of the piston is divided into a number of jets and the latter receive a whirling motion by reason of the inclination of the openings *G*, with the result that the mixture is

agitated and a thorough commingling of the constituents assured. When it is required to prime the carbureter the stem *b'* is drawn upward, thereby lifting the valve *8* from its seat so that the fuel may flood and a portion pass into the priming cup *j* to insure a rich mixture when starting the engine.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

Having thus described the invention what is claimed as new, is:—

1. In a carbureter of the character described, the combination of a spray nozzle, a piston having a hollow stem telescoping with the spray nozzle and having a lateral opening, said piston being provided with a plurality of openings inclined to the vertical, and a deflector mounted upon the hollow stem of the piston above the lateral opening.

2. In a carbureter of the character described the combination of a Venturi tube, a spray nozzle arranged to deliver the fuel centrally of the contracted portion, a piston movable in the Venturi tube above the upper flared portion and provided with a plurality of openings, and a hollow stem connected with the piston and telescoping with the spray nozzle and provided in a side with an opening at a point above and adjacent the extremity of the spray nozzle.

3. In a carbureter of the character described the combination of a Venturi tube, a spray nozzle arranged to deliver the fuel centrally of the contracted portion, a piston movable in the Venturi tube above the upper flared portion and provided with a plurality of openings, a hollow stem connected with the piston and telescoping with the spray nozzle and provided in a side with an opening at a point above and adjacent the extremity of the spray nozzle, and a deflector mounted upon the hollow stem and movable therewith and located above the lateral opening and adapted to close the contracted portion of the Venturi tube.

4. In a carbureter of the character described the combination of a Venturi tube, a spray nozzle arranged within the lower portion of the tube and terminating about in the plane of the contracted portion there-

of, a piston movable in the upper portion of the Venturi tube and provided with a plurality of openings inclined to the vertical, a hollow stem connected with the piston and telescoping with the spray nozzle and having an opening in its side about in the plane of the contracted portion of the Venturi tube, and a deflector mounted upon the hollow stem above the opening in the side there-

of and adapted to close the contracted portion of the Venturi tube.

In testimony whereof I affix my signature in presence of two witnesses.

PASQUALE J. SASSANO.
